PATENTED JAN. 7, 1908.

O. G. FRANKS.

SHORT RAIL FOR BEDS.

APPLICATION FILED MAR. 18, 1907.

UNITED STATES PATENT OFFICE.

ORRIN G. FRANKS, OF CHICAGO, ILLINOIS, ASSIGNOR TO THE SENG COMPANY, OF CHICAGO,
ILLINOIS, A CORPORATION.

SHORT RAIL FOR BEDS.

No. 875,703.

Specification of Letters Patent.

Patented Jan. 7, 1908.

Application filed March 18, 1907. Serial No. 363,031.

To all whom it may concern:

Be it known that I, ORRIN G. FRANKS, a citizen of the United States, residing at Chicago, in the county of Cook and State of Illinois, have invented certain Improvements 5 in Short Rails for Beds, of which the following is a specification.

This invention relates to the class of metal beds, and is more especially an improvement 10 in what are commonly known as short-rails and employed for the purpose of connecting the head and foot sections of the bed in substantially the same manner as the usual side rails but in closer relation to economize space 15 in exhibiting the principal parts of a metal bed.

The objects of the invention are to provide a construction of short-rail which can be cheaply manufactured; will securely and 20 firmly connect the sections of the bed so that they may be moved or shifted without affecting the rigidity of the connection; may be readily and conveniently applied; and will be durable in use.

25 Other though minor objects of the invention will hereinafter be apparent, and what I claim as new will be specifically set forth in the appended claims.

In the accompanying drawings: Figure 1 30 is an elevation showing the application of the invention. Fig. 2 is a vertical sectional view on the line 2—2 of Fig. 1. Fig. 3 is a similar view through one of the securing bolts, on the line 3—3 of Fig. 1. Fig. 4 is an 35 inverted plan view of the upper connecting plate. Fig. 5 is a plan view of the lower connecting plate.

Like numerals of reference indicate like 40 parts in all the figures of the drawings.

Referring to said drawings, 1 designates one of the corner posts of the head section of a metal bed, and 2 a corner post of the foot section, said posts being provided with the chilled rail-sockets 3 and 4, respectively, 45 having the usual dovetailed or keyhole shaped slots 5 which receive the ends of the side rails of the bed. As is usual these dovetailed or keyhole shaped slots 5 are tapered from top to bottom.

50 In carrying out my invention I employ two connecting plates, an upper plate 6 and a lower plate 7, and the ends of said plates are shaped so as to bear against the rail-sockets and engage within the ends of the 55 dovetailed slots, and are therefore similarly

shaped with the exception that the slot engaging portions of the upper plate are larger than the corresponding portions of the lower plate, to accommodate the respective ends of the slot. In the present instance these 60 plates are formed of stamped metal, and shaped so that the upper plate 6 will have near each end and on its under side a circular boss 6^a extended at its inner side, as at 6^b, adapted to take into the upper or larger end 65 of the slot 5 in the rail-socket; while the lower plate 7 is provided with a similar shaped boss 7^a and extension 7^b on its upper side and somewhat smaller so as to fit within the lower or smaller end of the aforesaid slot. 70 It will be understood, of course, that the larger or circular portion of each boss fits into the larger portion of the dovetailed or keyhole shaped slot in the rail-socket, and that the extension at one side of said circular 75 portion of the boss fits within the narrower portion of the slot. I prefer that the extensions of the bosses be continued along the longitudinal centers of the plates, as shown, so as to form strengthening ribs. The bosses 80 are preferably slightly beveled at their edges so that they will bind in the ends of the slots when clamped therein by the connecting bolts 8, and for the purpose of receiving these connecting bolts the larger or circular 85 portion of each boss is provided with an opening, the opening, as 9, in the plate 6 being round to receive the threaded end of the bolt, while the opening, as 10, in the plate 7 is square to receive the correspondingly shaped shoulder 8^a of the bolt to prevent rotation of the latter when the securing nut is turned. In connection with the bolts 90 winged thumb-nuts 11 are employed and are adapted to bear upon the upper plate 6, and 95 in order that the bottom of the nut will be on a line with the upper surface of the plate the depressed boss 6^a is raised around the bolt-opening, as indicated at 6^c.

In applying a short-rail constructed as 100 hereinbefore described the thumb-nut at one end is loosened and the bolt and ends of the plate are slid laterally into engagement with one of the rail-sockets, the nut being then partly tightened to loosely connect the 105 plates to said socket. The thumb-nut at the other end of the short-rail is then loosened and the other rail-socket moved so that it will slide in between the ends of the plate. Both thumb-nuts are now tightened to se- 110

curely and firmly clamp the plates to the sockets and thus connect the sections of the bed rigidly together. It will be understood, of course, that two short-rails are used in connection with each metal bed, one for each side of said bed.

In applying and removing the short-rails it is not necessary to remove the thumb-nuts, but simply to loosen them sufficiently to 10 permit the rail-sockets of the bed sections to slide in between the ends of the plates, and in this operation the bolts pass into the key-hole slots and lie within the larger portions thereof.

15 When the plates are applied and clamped against the upper and lower sides of the rail-sockets the bosses on said plates will intimately engage into the opposite ends of the dovetailed or keyhole shaped slots and will 20 thus prevent any play at the connections or joints, thereby rigidly connecting the sections of the bed so that they will not wobble or become loose when moved or shifted in exhibiting the bed.

25 It will be seen that the construction provides a very simple, effective and inexpensive form of short-rail for metal beds, and one that can be put in use a number of times without affecting its gripping or clamping 30 qualities.

Having described my invention, I claim:

1. In a short rail for metal beds, the combination with the rail-sockets having vertical slots therein, of plates bearing against the 35 upper and lower ends of the sockets, bosses projecting inwardly from the plates and closely fitting in the ends of the slots, and bolts for connecting the plates and clamping them against the ends of the sockets 40 with the bosses engaging the slots, substantially as shown and for the purpose set forth.

2. In a short-rail for metal beds, the combination with the rail-sockets having vertical slots therein, of plates bearing against the 45 upper and lower ends of the sockets, bosses projecting inwardly from the plates and engaging in the ends of the slots, the engaging

edges of said bosses being beveled, and bolts for connecting the plates and clamping them against the ends of the sockets, substantially 50 as shown and described.

3. In a short-rail for metal beds, the combination with the rail-sockets having vertical slots therein, of upper and lower plates having bosses on their inner faces adapted to fit 55 into the ends of the slots in the rail-sockets, said plates having bolt-holes extending through the bosses, bolts engaging the bolt-holes, and nuts threaded on the bolts and adapted to clamp the plates against the rail- 60 sockets.

4. In a short-rail for metal beds, the combination with the rail-sockets having vertical slots therein, of upper and lower plates having bosses on their inner faces with bolt-holes 65 therethrough, the bolt-holes in one of the plates being rectangular, bolts engaging the bolt-holes and having shoulders which engage the aforesaid rectangular openings, and winged nuts threaded on the bolts to clamp 70 the plates against the rail-sockets and so that the bosses engage into the ends of the slots therein.

5. In a short-rail for metal beds, the combination with the rail-sockets having vertical 75 slots therein, of upper and lower clamping plates formed of stamped metal to provide bosses near their ends connected by a depressed rib extending longitudinally of the plate, said bosses being shaped to engage the 80 opposite ends of the slots in the rail-sockets and pierced to provide bolt-holes, connecting-bolts engaging said bolt-holes, and winged nuts threaded on the bolts and adapted to clamp the plates against the rail-sock- 85 ets, substantially as shown and described.

In testimony whereof I have signed my name to this specification in the presence of two subscribing witnesses.

ORRIN G. FRANKS.
